CENTRIFUGAL COMPRESSOR

Emery C. Furrer, Chicago, Ill.

Application September 28, 1936, Serial No. 102,931

6 Claims. (Cl. 230—128)

This invention relates to improvements in centrifugal compressors.

One object of the invention is to provide a centrifugal or turbo compressor for gases which is so constructed as to effect a reduction in energy losses between stationary and moving parts by means of fluid seals between such parts.

Another object of the invention is to provide a centrifugal compressor having preferably a plurality of radially disposed spaced apart compression chambers each of which is cooled by air moved between the same by the rotary movement of the chambers.

A further object of the invention is to provide a rotary compressor arranged to draw the air, or other gas to be compressed, into the machine in opposite axial directions to effect a mutual counter-balancing of the rapidly flowing incoming gases to reduce or eliminate shock losses caused thereby.

Other objects of the invention relate to various features of construction and arrangement of parts which will be apparent from a consideration of the following specification and accompanying drawing wherein:

Figure 1 is a side elevation of a centrifugal compressor embodying the present improvements.

Figure 2 is an enlarged sectional view taken on line 2—2 of Figure 1.

Figure 3 is a further enlarged broken vertical section taken on line 3—3 of Figure 2.

Figure 4 is an enlarged broken vertical sectional view taken on line 4—4 of Figure 2.

Figure 5 is an enlarged section taken on line 5—5 of Figure 3.

In Figure 1 of the drawing, the apparatus shown is mounted adjacent a wall 10 of a building for support thereby and is provided with two inlet ducts 11 and 12 for conveying to the compressor the air to be compressed. It will be understood that one or both such ducts may be connected to a supply of other gas where such other gas is to be compressed by the machine.

The duct 11 connects at its inner end to a hollow shaft 13, see Fig. 3, which shaft is supported by upper and lower bearings 14 and 15. The shaft 13 is also provided with a pulley 16 around which operates a belt 17 extending to an electric motor 18 or other source of power for effecting the rotation of the shaft. The duct 12 is of considerably greater diameter than duct 11 and bearing 15 is supported therein by any suitable means as by beam 15a.

Extending from the hollow shaft 13 are a plurality of radially disposed compression chambers

19 which decrease in cross sectional area from the inner to the outer ends thereof. The chambers 19 are spaced apart to provide passages for the flow of cooling air around the chambers and are provided with heat radiating or cooling fins 19a. 5

The upper and lower ends of the shaft 13 are provided with blades 20 which are somewhat fan shaped and which are shaped at their edges to move the air from the ducts 11 and 12 inwardly toward a centrally arranged deflecting plate 21. 10 The blades also provide a structural support for the shaft 13, the inner ends of the blades being united to a central shaft or core 22. It will be observed that as the shaft 13 rotates, air will be drawn from the ducts 11 and 12 inwardly through 15 each end of the shaft toward the deflector plate 21 which directs the air radially into the various compression chambers 19. Due to the decreasing cross sectional area of the chambers 19, the air is compressed under the influence of the centrifugal 20 force developed by the rapidly rotating chambers and passes from the chambers into a hollow rim or annular connecting member 23 which unites the chambers at their outer ends.

As is shown in Fig. 2, the portions 23a of the 25 rim 23 between adjacent arms decrease in cross sectional area from the forward ends to the rear ends thereof, the structure being designed for rotation in a counter-clockwise direction as viewed in Fig. 2. Air in passing from the chambers 19 into the various rim sections 23a is consequently further compressed and passes from the rim into air receivers 24, two of which are shown, which terminate in ducts 25 which convey the compressed air to a place of storage or 30 use. The receivers 24 are stationary and decrease in cross sectional area from the outlet ends which are connected to the conduits 25. 35

The rim sections 23a preferably are provided with a number of spaced apart walls or partitions 40 23b between which the air passes in flowing from the ends of the chambers 19 into the receivers 24.

The hollow rim 23 is, as shown in Fig. 4, provided on its upper surface with three annular walls 27, 28 and 29, the first two of which are 45 shown as being slightly curved at their extremities. Each receiver 24 is provided with a neck 24a which is somewhat enlarged at its inner periphery and terminates in a horizontal wall 24b which is provided with oppositely curved depending annular walls 30 and 31. It will be seen that between walls 27 and 28 a chamber 32 is provided in which sealing liquid may be retained and which in cooperation with the walls 27 and 30 will provide a seal to prevent the escape of compressed 50 55

air through the space between the outer periphery of the rim and the adjacent portion of the receiver.

Between walls 28 and 29 another chamber 33 is provided for retaining sealing liquid which in cooperation with walls 28 and 31 will provide a further seal against the escape of compressed gas. The rim is also provided with depending walls 34 and 35 which project into the spaces or liquid chambers defined by walls 36, 37 and 38 which are carried by the necks 24a of the receivers 24. The lower extremities of the walls 34 and 35 are shown as being provided with thin plates 39 which extend into close proximity with the walls 40 which connect the walls 36, 37 and 38 to break up and reduce eddy currents in the liquid during the rapid rotation of the compressor.

It will be apparent that the thin plates 39 will wear away readily should they contact the wall 40 and that the plates therefore can be set initially close to the wall 40 without subsequent damage to the parts should they contact during operation. It will be noted that while the upper and lower fluid seals shown in section in Fig. 4 are similar in principle, they differ slightly in structural detail for the reason that the fluid of the upper seal is carried by the rotary structure, while the fluid of the lower seal is carried by members supported by the stationary receivers.

It will be observed that as the rotary structure of the compressor is operated air will be drawn into the ducts 11 and 12 partially by the fan action of the blades 20 and partially by the centrifugal action of the air initially present in the structure. The air will move radially through the compression chambers 19 and be compressed as it is forced to travel by centrifugal action through the constantly reduced cross sectional area of the chambers. It then passes from the chambers into the rim sections between the walls 23b thereof and is thence directed between blades 24c disposed in the neck 24a of the receivers 24. The stationary blades 24c are so disposed as to effect a reaction on the air issuing from the rim and converts the velocity head into pressure head as it passes into the receivers 24.

During such rotation of the apparatus the liquid in the respective sealing chambers tends to move radially outwardly or to the left as viewed in Figure 4 by the centrifugal action of the machine and will assume substantially the positions indicated in Fig. 4 in which positions it will be noted that compressed air cannot escape between the rim and the receivers. The greater the back pressure of the air due to centrifugal action, the greater will be the resisting force exerted by the liquid. The fluid sealing means described not only provides an adequate seal between the relatively movable parts of the apparatus, but greatly reduces energy losses due to friction.

The chambers 19 are provided on their outer walls with horizontal blades 41 as shown in Fig. 5, which are shaped to produce an inward flow of air through the duct 12 and upwardly into heat transfer relation with the surfaces of the chambers 19 and the fins 19a to absorb the heat of compression generated by the compression of the air. Stationary vanes 42 preferably are secured to the interior of the duct 12 to deflect the air in the direction of rotation of the chambers to reduce shock.

To avoid the transfer of heat to the duct 11 from the rising air a sheath 43 is provided around the duct as shown in Figs. 1 and 3.

In operation the compressor is operated at the

velocity required to effect the desired compression of the air or the other gas. Due to the dual intake arrangement whereby the incoming air flows in opposite direction through the equal capacity intake ends of the shaft 13 to the center of the machine toward the distributor plate 21, the shock or thrust of the incoming air is balanced at all speeds of operation. It will also be noted that increasing the rotary velocity of the machine to increase its output of compressed air or the degree of compression thereof, increases also the flow of air around the exterior of the compression chambers to absorb the increased heat of compression and that increase in back pressure due to velocity, which tends to effect escape of air between the annular rim 23 and the annular receivers increases the resistance of the fluid in the sealing chambers to resist such tendency.

It will be understood that if a gas other than air is to be compressed, the duct 11 and the lower end of the hollow shaft 13 will be connected to the source of supply of such gas. The flow of air through the duct 12 will be utilized, as above described, for cooling the compression chambers.

While I have shown and described an embodiment of my invention for the purpose of illustration, I do not wish to be restricted specifically thereto except as so limited by the appended claims.

I claim:

1. A gas compressor comprising a rotary structure having intakes disposed for admitting gas thereto axially of the structure and in opposite directions, radially disposed rotary compression chambers communicating with said intakes and provided with passages for the flow of cooling air between adjacent chambers, and a stationary receiver for receiving gas compressed by the chambers and provided with an elongated arcuate intake disposed in communication with the outer ends of said chambers, said receiver having cross-sectional areas increasing progressively in the direction of rotation of said chambers.

2. A gas compressor comprising a rotary structure, means for rotating the same, said structure having an axial gas intake and radially arranged compression chambers communicating therewith for centrifugally compressing gas flowing into the same, a gas receiver having an elongated arcuate intake communicating with the ends of said chambers, and means for effecting the flow of air axially of the structure between said chambers for absorbing the heat of compression of the gas therein.

3. A gas compressor comprising a rotary structure having an axial gas intake, a plurality of radially arranged rotary gas compression chambers communicating therewith, an annular hollow rim communicating with and connecting the outer ends of said chambers and provided with an open outer periphery, the segments of said rim between adjacent chambers decreasing in cross sectional area from the forward to the rear ends of said segments, a stationary gas receiver disposed adjacent the outer open periphery of said rim for receiving gas therefrom, and inter-leaving projections carried by adjacent portions of said rim and receiver defining annular fluid-confining channels for a fluid to prevent escape of gas in the passage of the same from said rim to said receiver.

4. A gas compressor comprising a rotary structure having an axial gas intake, a plurality of

radially disposed rotary chambers communicating with said intake, a hollow rim connecting the outer ends of said chambers and communicating therewith, said chambers from the inner 5 to the outer ends thereof and the sections of said rim between adjacent chambers from the forward to the rear ends thereof decreasing in cross-sectional area for effecting the compression of the gas forced centrifugally therethrough, and a 10 stationary gas receiver communicating with said rim.

5. A gas compressor comprising a rotary structure provided with a hollow shaft disposed axially of the structure and provided with a gas intake 15 at each end thereof, a plurality of spaced apart radially disposed compression chambers communicating with said shaft, a hollow rim connected to and communicating with the outer ends of said chambers and provided with an open outer periphery, stationary annular receiving means communicating with the open periphery of said rim, fluid sealing means comprising co-

operating stationary and rotary portions carried respectively by said receiving means and said rim to prevent escape therebetween of compressed gas, and blades carried by said chambers for effecting the circulation of air between the latter for absorbing heat generated by the compression of the gas therein. 5

6. In a gas compressor, a rotary structure comprising a plurality of radially arranged compression chambers decreasing in cross sectional 10 area from the inner to the outer ends thereof for compressing gas passing therethrough, said structure being provided with an axial gas intake common to said chambers, an annular stationary gas receiver having a gas receiving passage in its inner periphery, and a continuous hollow rim at the outer ends of said chambers provided with an outer annular outlet in sealed communication with the gas receiving passage of said receiver for transferring compressed gas 15 20 from said chambers to said receiver.
